UNITED STATES PATENT OFFICE

163,360

SHOE OR SIMILAR ARTICLE

Walter Braun, Los Angeles, Calif., assignor to Cobblers Incorporated, Los Angeles, Calif., a corporation of California

Application January 25, 1951, Serial No. 13,977

Term of patent 7 years

(Cl. D7—7)

To all whom it may concern:

Be it known that I, Walter Braun, a citizen of the United States, residing in Los Angeles, in the county of Los Angeles, State of California, have invented a new, original, and ornamental Design for a Shoe or Similar Article, of which the following is a specification, reference being had to the accompanying drawing, forming a part thereof.

Figure 1 is a side elevational view of a shoe, showing my new design as it appears when being worn, the representation of a human foot and angle in broken lines is for illustrative purposes only.

I claim:

The ornamental design for a shoe or similar article, as shown and described.

WALTER BRAUN.
